CLOSURE

Lillian Shapiro, Brooklyn, N. Y., assignor, by
mesne assignments, to Columbia Plush & Puff
Co. Inc., Brooklyn, N. Y., a corporation of New
York

Application March 5, 1935, Serial No. 9,378

3 Claims. (Cl. 24—207)

This invention relates to closures, particularly of the type adapted for use with purses, cosmetic bags, tobacco pouches and the like, as well as for wearing apparel such as shirts where it can be employed in place of buttons.

There are various closure devices for similar purposes, such as interlocking slide fasteners, and those comprising a plurality of spaced elements attached together by suitable linkage and slidably mounted over adjacent beads or rails. The former, although efficient, are relatively expensive and of a definite and fixed configuration generally not considered very ornamental; and the known types of the latter, to which class my invention belongs, although adaptable to ornamental design, have laterally exposed chains, and do not effect a close sealing, particularly along the spaced intervals between the slideable elements unless there is a superimposition of one of said rails upon the other, and a consequent bending or distortion thereof. It is hence an object of my invention to improve over the known art by enabling a simple, inexpensive device of this class, capable of ornamentation, and consisting of a number of spaced slideable elements, to effectively bring into contiguous juxtaposition adjacent beaded closure edges to produce a satisfactory seal.

Another object of this invention is to permit the slideable elements to be operatively movable with a minimum of friction against the beaded edges upon which they are mounted.

Other objects, features and advantages will appear from the drawings and the description hereinafter given.

Referring to the drawings,

Figure 1 is a perspective view of a closed bag containing my invention.

Figure 2 is a perspective of the bag of Figure 1 opened.

Figure 3 is a fragmentary vertical longitudinal section taken along the centers of the slideable elements of Figure 1.

Figure 4 is a fragmentary vertical section taken along line 4—4 of Figure 3.

Figure 5 is a view similar to Figure 4, showing a modified form of slide.

Figure 6 is a plan view of Figure 5.

Figure 7 represents another form of slide adaptable for use in my invention.

Figure 8 is a vertical section taken along line 8—8, of Figure 7.

Figure 9 is still another modified form of slide, showing a separate retaining piece for the chain.

Figure 10 discloses another adaptation of my

invention, illustrating its use on a shirt shown closed.

Figure 11 shows the device on the shirt of Figure 10 when opened.

Figure 12 illustrates still another form of shirt closure, and

Figure 13 is an enlarged transverse section taken along line 13—13 of Figure 12, showing the general configuration of a duplex slide.

In the drawings, the bag 15 contains at the opening thereof two adjacent, preferably semi-stiff closure beads or rails 16 and 17 over which are mounted a plurality of movable elements or slides 18 and one fixed binding element 19. These slides, in their operative positions, as shown in Figure 1, are in spaced relation, and are connected by the flexible link or chain 20 suitably secured preferable to the centers of the slides 18 and the binding 19, and positioned longitudinally above the contacting edge of said beads.

In the preferred form of my invention, the slide contains retaining means for the chain integral therewith, including the lower supporting wall 21 pressed downwardly from the middle of the slide into the space 22 between the tops of the beads. This supporting wall cooperates with the upper side walls 23 and 24 to hold the chain 20 therebetween, all of said walls being preferably compressed towards the chain to hold it against movement, as is indicated in Figure 3.

The lateral sides 25 and 26 of the slides are inwardly curved as shown, so as to contact preferably with the lower portions of the beads 16 and 17, and with the upper adjacent portions of the sides 27 and 28 of the bag to compress them together.

The curved indents at the bottoms of said lateral sides 25 and 26 are so formed and dimensioned as to be in pressing engagement with the underportions of the beads and with the sides of the bag, and yet adaptable for sliding engagement therealong.

The top or upper portion of each slide may be spaced somewhat from the tops of the beads, as shown in Figure 4.

In the operation of this device, the elements 18 can be slidably moved along the beads 16 and 17, to open or close the bag, the stationary binder 19 being immovably compressed at an end thereof.

When the bag is in its closed position, sides 25 and 26 of the slides, being in pressing engagement as hereinabove set forth, hold the beads in firm contiguous juxtaposition; and as these slides are frictionally held in place against movement, they will be enabled, in their spaced operative positions, to hold the chain 20 taut.

Inasmuch as this chain is positioned over the

opening edge of the bag, it will serve as a further seal therealong to prevent the contents of the bag from dropping out when it is inverted, as might occur between the slides if the chain were not present. For most effective sealing, I prefer to use a relatively wide chain.

It will be noted that inasmuch as the slides need not be in contact with the upper portion of the beads, there is relatively little frictional resistance to sliding. Furthermore, such an arrangement avoids excessive wear along the top of the beads. Inasmuch as the supporting wall 21 is depressed downwardly and extends into the space 22, the chain 20 is supported at a relatively low level, and close to the top opening edge of the bag. It is also quite apparent that this form of closure is quite simple, the entire slide being formed from a single strip of metal.

In Figures 5 and 6 is shown a modified form of slide 29 containing a centrally disposed transverse channel 30 pressed downwardly from the top of the slide to accommodate the chain 31. The top of the channel is compressed together about the chain, to hold it against movement and to properly retain it in place. This is also an integral unitary member, the lateral sides thereof being similar to those of the said preferred form.

Figures 7 and 8 show another modification of the slide, the chain retaining elements being the overhanging walls 32 containing the holes 33 therein to accommodate the chain. And Figure 9 shows still another form of my invention, the slide consisting of two members, the slide proper 34 and the chain retaining element 35 the ends of which are inserted in suitable holes in the slide and compressed into place against the chain.

My invention is not only adaptable for use with bags and pouches, but is also applicable to wearing apparel, particularly in shirts and blouses of various kinds. By referring to Figure 10, it will be seen that the two parallel adjacent beads 36 and 37 attached to the shirt have slidably mounted thereover the slides 38 and the fixed binder 39, the slides being interconnected by the chain 40. The shirt can be opened by drawing the slides downwardly, as shown in Figure 11.

Another form of closure particularly applicable to shirts is that disclosed in Figures 12 and 13. Here the pieces of material 41 and 42 are not compressed together, but permitted to extend outwardly in opposite directions, the duplex guide 43 operatively embracing both beads 44 and 45, the chain 46 being held into place by the retaining wall 47 pressing it against the body of the slide as shown. It is apparent that with this construction the two contiguous beads do not protrude an undue amount forwardly from the body of the shirt.

It is of course understood that the various embodiments above described and shown in the drawings are illustrative of my invention and not employed by way of limitation, inasmuch as

numerous changes and modifications may be made within the scope of the appended claims without departing from the spirit of this invention.

What I claim is:

1. In combination with two adjacent longitudinal beads adapted for contiguous engagement to form a seal therealong, a closure containing a plurality of elements slidably mounted over said beads and having chain retaining means each comprising a lower supporting wall pressed downwardly from the middle of the element above the line of engagement of the two beads, and two upper substantially flat side walls of the element flanking said supporting wall, and a chain extending above said supporting wall and below said side walls and compressed therebetween; said slideable elements each having two lateral sides with curved indents at the bottoms thereof in pressing engagement with the lateral sides and lower portions of the beads, the upper portion of each of said elements being out of engagement with the upper portion of the beads.

2. In combination with two adjacent longitudinal beads adapted for contiguous engagement to form a seal therealong, a closure containing a plurality of elements slidably mounted over said beads and having chain-retaining means above the line of engagement of the two beads, each comprising a substantially flat top portion and lower supporting means pressed downwardly therefrom, and a chain extending below the flat portions and above the said lower supporting means and compressed therebetween; said slideable elements each having two lateral sides with curved indents at the bottoms thereof in pressing engagement with the lateral sides and lower portions of the beads, the upper portion of each of said elements being out of engagement with the upper portion of the beads.

3. In combination with two adjacent longitudinal beads adapted for contiguous engagement to form a seal therealong, closure means including a plurality of elements slidably mounted on said beads and having retaining means for a flexible connecting member above the line of engagement of the two beads, each member comprising a substantially flat top portion and supporting means pressed downwardly therefrom, and a flexible connecting member extending below the flat portions and above the supporting means of said members and compressed therebetween to secure said members to said flexible connecting member, said slideable elements each having sides with curved indents at one end thereof arranged in pressing engagement with the sides and lower portions of the beads to hold the beads in contacting and sealed relation, the upper portion of each of said elements being out of engagement with the upper portions of the beads.

LILLIAN SHAPIRO.
